UNITED STATES PATENT OFFICE.

HARRY A. ROE, OF CHICAGO, ILLINOIS, ASSIGNOR TO SAUERMAN BROS., INC.

MATERIAL-MOVING APPARATUS.

Application filed March 26, 1927. Serial No. 178,714.

My invention relates to drag-scraper apparatus for use more particularly, in transferring loose material from one point to another, as for example in the excavating of 5 earth, in transferring minerals, such as coal, from one point to another, and in the conveying of materials in general, and involving in such transferring operation along a predetermined path, a change of direction of 10 movement of the scraper either in a substantially horizontal or vertical plane.

My object, generally stated, is to provide a novel, simple and inexpensive construction of apparatus by which, under the control of 15 an operator, the scraper may be caused to travel in such a path, without producing undue wear of the parts of the apparatus and be operable at different speeds without requiring expensive machinery; and other objects as will be manifest from the following 20 description.

Referring to the accompanying drawings:

Figure 1 is a plan sectional view of a portion of a coal mine equipped with apparatus, 25 constructed in accordance with my invention, for transferring the loose coal deposited on the floor of the mine in the mining operation, to a point of discharge and involving the transferring of the coal along a predetermined path, portions of which extend at 30 an angle to each other in a substantially horizontal plane. Figure 2 is a perspective view of the scraper portion of the apparatus and illustrating one form of embodiment of my invention. Figure 3 is a plan view of a 35 modification of the scraper device. Figure 4 is a view in side elevation of the structure shown in Fig. 3. Figure 5 is a plan view of still another modification of the scraper device. Figure 6 is a view in side elevation 40 of the apparatus of Fig. 5. Figure 7 is a broken, enlarged sectional view of a portion of the structure shown in Fig. 5, the section being taken at the line 7 on Fig. 5 and viewed 45 in the direction of the arrow. Figure 8 is an elevational view, somewhat in the nature of a diagram, of apparatus for excavating earth and involving, in such operation, a change in direction of movement of the 50 scraper in a substantially vertical plane, the apparatus being shown in operative position

for effecting the excavating function and constituting an embodiment of my invention. Figure 9 is a plan view of the apparatus of Fig. 8. Figure 10 is a section taken at the 55 line 10 on Fig. 9 and viewed in the direction of the arrow; and Figure 11, a broken, enlarged elevational view of a derrick forming a part of the apparatus of Figs. 8 and 9.

Referring to Fig. 1 of the drawings, this 60 view shows a portion of a mine, as for example a coal mine, 12 representing the face of the body of coal being mined, the dislodged coal in the mining operation falling onto the floor 13 of the mine adjacent the face 12 and 65 from which it is desired the coal be moved down the gallery 14 to the gallery 15 for discharge into a receiver 14^a shown as a chute for directing the material into a car, (not shown), operating in the gallery 15 on tracks 70 16 therein, it being understood from the foregoing that in transferring the coal from the face 12 through the gallery 14 to the point of discharge, it is moved along a predetermined path with portions of the path extending at 75 angles to each other in a substantially horizontal plane due to the necessity of carrying the coal around the corner 17 of the mass 18 of unmined coal.

The apparatus by which the mined coal is 80 conveyed as stated and embodying my invention comprises a scraper 19 which may be of any suitable type, as for example of the so-called bottomless-scraper type, connected at its forward, filling, end with an inhaul line 85 20; at its rear end with a back-haul line 21 and operatively associated with a third line 22 as hereinafter described. The inhaul line 20 is shown as engaging a sheave 23 and thence to a winding drum 24 to which it is 90 connected. The back-haul line 21 is shown as passing around a sheave 25 secured to an adjacent wall 26 of the mine, and preferably adjustable, in any suitable way, lengthwise along the wall 26, this line also engaging a 95 sheave 27 secured to the adjacent wall 28 of the mine and adjustable in any desirable way along the latter, this line thence extending into engagement with sheaves 29 and 30 and to a winding drum 31 to which it is connected. The line 22 engages a sheave 32 secured to a wall 33 of the gallery 14 in any 100

suitable manner to render it adjustable along this wall and thence extends into engagement with sheaves 34 and 35 and to a winding drum 36 to which it is connected, one of the 5 positions to which sheave 32 is adjustable being shown in dotted lines on Fig. 1. All of these winding drums in practice, would be, preferably, independently operative under the control of the operator and provided 10 with friction brake devices in accordance with common practice.

Referring now to the operative connection of the line 22 with the scraper apparatus 19, Fig. 2 shows a well-known type of so-called 15 bottomless scraper, the line 20 being connected with the forward end of the scraper through the medium of a clevis 37 and a bridle 38 the sections of which connect with the forward extremities of the sides of the 20 scraper, the line 21 being connected with the rear end of the scraper midway between the sides of the latter through the medium of a bracket 39. Connected at its opposite depending arms 40 and 41, with the clevis 37 25 and rigidly with the bracket 39, respectively, is a yoke-shaped slideway 42 which is preferably slightly flexible and to this end may be made of steel, this yoke being preferably provided with a stop button 43 on the rear arm 30 41. The slideway 42 is thus positioned above the scraper 19 and extends preferably substantially parallel with the longitudinal axis of the scraper and midway of the sides of the latter. The hauling line 22 operatively 35 engages the scraper 19 through the medium of the slideway 42 the connection between these parts being at a ring 44 connected with the line 22 and surrounding the slideway 42 along which it is slidable from the clevis 37 40 to the stop 43.

In the operation of the apparatus for transferring coal from the face 12 to the chute 14^a, and assuming the parts of the apparatus to be in the position shown in Fig. 1, the 45 winding drum 36 is actuated to draw on the line 22 which latter in engaging the arm 40 drags the scraper from its front end along the coal to be transferred, the drum 24 in this 50 operation being driven to take up the slack in line 20 and the drum 31 being left free to rotate so that the line 21 may pay out in this movement of the scraper. After the scraper 19 reaches a position in line with the gallery 14, the operator actuates the drum 24 to 55 thereby draw the scraper down the gallery 14 to the chute 14^a by means of the line 20, the line 21 continuing to pay out and the drum 36 being conditioned to permit the line 22 to pay out also. The return of the scraper 60 19 to filling position at the face 12 of the mine is effected by drawing the scraper backwardly along the gallery 14 to a position beyond the face 12 by drawing on the line 22, the line 20 paying out in this operation and 65 the drum 31 being actuated to take up the

slack in line 21, it being understood that in the movement of the scraper 19 into the gallery 14 the line 22 runs along the slideway to the rear end of the scraper until it engages with the stop 43 and thus when the line 22 is drawn 70 upon as stated it engages the stop 43 and thereby operates as a back-haul line. Upon completing the return movement of the scraper 19 to a position beyond the face 12 by operating the line 22 as stated, the line 21 75 is operated, both lines 20 and 22 paying out in this operation, to drag the scraper backwardly along the face 12 to filling position.

It will thus be understood from the foregoing description that the line 22 operates 80 alternately as an inhaul line and a back-haul line, the inhaul function being performed in the movement of the scraper along the face 12 of the mine to a point beyond the corner 17 and the back-haul function being performed in the moving of the scraper backwardly from its point of discharge along the gallery 14 to a position beyond the face 12, the arrangement provided for causing the scraper apparatus to function as stated not 85 only being of simple and inexpensive construction and positive in operation, but overcoming the necessity of drawing any of the lines in taut condition against the corner portion of a mass of material. 95

Figs. 3, 4, 5, 6 and 7 show modifications of the slideway by which the automatic shifting of the line 22 relative to the scraper to cause this line to function alternately as an inhaul and a back-haul line, is effected. In 100 the construction shown in Figs. 3 and 4 the slideway represented at 45 and shown as of general yoke form is secured to the scraper 19 wholly independently of the lines 20 and 21, the front end of this yoke being directly 105 connected with the forward extremities of the side of the scraper 19 through the medium of converging arms 46 and its rear end connected with the rear portion of the scraper by similarly disposed arms 47, the line 21 110 in this construction being connected with the scraper through the medium of a bridle 48, and the line 20 with the forward end of the scraper through a bridle 49 like the bridle 38. 115

In the construction shown in Fig. 5 the 120 slideway for the line 22 instead of extending over the top of the scraper extends around a side thereof. The slideway of this construction is represented at 50 and is shown as formed of a yoke-bar substantially H-shape in cross section affording upper and lower grooves 51 and 52 in which rollers 53 and 54 journalled in a clevis 55 and connected with the line 22 are confined. The slideway 50 which extends from the rear end of the 125 scraper substantially from a point midway between the sides thereof to a point at the front end of the scraper substantially coincident with the longitudinal axis of the scraper, is located substantially midway be- 130

tween the upper and lower edges of the 5 scraper, the forward end of this guideway being provided with an eye 56 for attachment thereto of the line 20 and its rear end provided with an eye 57 for attachment with the line 21, a bar 58 connected with the eye 56 and with the side of the scraper opposite that at which the slideway 50 extends, serving, in connection with the forward extremity of the 10 slideway 50, to equalize the pull on the scraper when the scraper is being pulled by the line 20. Preferably the forward ends of this scraper are braced, as for example by the cross member represented at 59.

15 The sheaves 25 and 32 being adjustable as stated permit of the changing of the angle of the path through which the scraper is operated, as desired, and the changing of the path through which the scraper moves in 20 traversing the face 12 of the mine, to cause the scraper to be operated along this face as the latter recedes in the mining operation.

25 My invention is useful not only where the scraper in its movement in a predetermined path involves a change in direction of travel in a substantially horizontal plane as described, but also where such change of direction is in a substantially vertical plane as for example in the case of excavating earth in 30 which connection it is illustrated in Figs. 8, 9, 10 and 11. In these figures the earth is shown as being excavated at 60, the side wall of the excavation being shown at 61 and the spoil pile at 62, the operation of producing 35 the excavation 60 involving the dragging of the scraper along the substantially horizontal bottom 63 of the excavation and thence upwardly along the side 61 thereof to the spoil pile, there being thus provided a corner portion represented at 64 at the juncture of the 40 wall 61 and the lever 65 of the earth adjacent the excavation.

45 In the arrangement shown the scraper is represented at 66, its forward end being connected with an inhaul line 67 engaging a sheave 68 supported on a travelling carriage 69 and extending into engagement with a sheave 70 on a derrick 71 and thence to a winding drum 72. The rear end of the 50 scraper is connected with a back-haul line 73 running over a sheave 74 secured to a carriage 75 located in the excavation 60, and thence over a sheave 76 on the derrick 71 to a winding drum 77 to which it is connected. 55 The apparatus also involves a line 78 which has sliding engagement with a slideway represented at 79 and operatively connected with the scraper 66 as explained of the construction shown in Figs. 1 and 2; this line running over a swiveled flexibly-hung sheave 80 supported on the derrick 71 and thence leading to a winding drum 81 to which it is connected.

60 Assuming the various parts to be in the 65 various positions shown in Figs. 8 and 9, to

return the scraper 66 to excavating position, the line 78 is drawn on and the line 67 paid out and the slack taken up in the line 73, until the scraper has reached a position substantially in front of the derrick 71, and the 70 movement of the scraper to filling position continued by drawing on the line 73 and paying out the lines 67 and 78. The filling of the scraper and its movement to the point of discharge on the spoil pile 62 is effected by 75 first drawing on the line 78 in which operation the slack is taken up in line 67 and line 73 paid out, until the scraper in moving to the right in Figs. 8 and 9, passes the corner 80 64 whereupon the movement of the scraper to dumping position is continued by drawing on the line 67 while paying out the lines 73 and 78. Thus the line 78 operates alternately to perform the inhaul and back-haul functions, and by its use sliding of any of the 85 lines in engagement with the corner-portion 64 is prevented.

Another advantage resulting from the employment of my invention is that the scraper, by proper selection of the rope speeds of the 90 respective drums, may be caused to travel in portions of its forward and back movements at different speeds without requiring the use of multiple-speed hoisting drums.

95 While I have illustrated and described certain particular embodiments of my invention and the application thereof to certain uses, I do not wish to be understood as intending to limit it thereto as the same may be embodied in other forms of structure and applied to 100 different uses.

What I claim as new, and desire to secure by Letters Patent, is:

1. In material-moving apparatus, the combination of a scraper element, an inhaul line 105 and a back-haul line operatively connected with said element, and a power-operated third, inhaul, line operatively connected with said element and operative, independently of said first-named inhaul line, to move said element in a path at an angle to the path traveled by said element when the latter is operated solely by said first-named inhaul line.

110 2. In material-moving apparatus, the combination of a scraper element, an inhaul line and a back-haul line operatively connected with said element, and a third, inhaul and back-haul, line operatively connected with said element and operative to move said element in paths at angles to the respective paths traveled by said element when the latter is operated solely by said first-named inhaul and back-haul lines, respectively.

115 3. In material-moving apparatus, the combination of a scraper element, an inhaul line and a back-haul line operatively connected with said element, and a third, hauling, line operatively connected with said element and automatically shiftable from one end to the 120 125

other of said element to cause it to function alternately as an inhaul line and a back-haul line, for the purpose set forth.

4. In material-moving apparatus, the combination of a scraper element, an inhaul line and a back-haul line operatively connected with said element, a third line and a slideway along which said third line is movable along said element from one end to the other 10 of the latter, for the purpose set forth.

5. In material-moving apparatus, the combination of a scraper element, an inhaul line and a back-haul line operatively connected with said element, a third line and a slideway 15 on said element along which said third line is movable along said element from one end to the other of the latter, for the purpose set forth.

6. In material-moving apparatus, the combination of a scraper element, an inhaul line 20 and a back-haul line operatively connected with said element, a third line, and a laterally yieldable slideway adjacent said element and along which said third line is movable along said element from one end to the other 25 of the latter, for the purpose set forth.

7. In material-moving apparatus, the combination of a scraper element, an inhaul line 30 and a back-haul line operatively connected with said element, a third line, stops adjacent opposite ends of said element, and a slideway along which said third line is movable into engagement alternately with said stops, for the purpose set forth.

8. In material-moving apparatus, the combination of a scraper element, an inhaul line 35 and a back-haul line operatively connected with said element, a power-operated third outhaul line operatively connected with said element and operative, independently of said first-named inhaul line, to move said element in a path at an angle to the path traveled by said element when the latter is operated solely by said first-named inhaul line, and a 40 sheave engaged by said third line and adjustable to vary the path through which the element is moved by said third line.

9. In material-moving apparatus, the combination of a scraper element, an inhaul line 50 and a back-haul line operatively connected with said element, a third inhaul and back-haul, line operatively connected with said element and operative to move said element in paths at angles to the respective paths traveled by said element when the latter is operated solely by said first-named inhaul and back-haul lines, respectively, and a 55 sheave engaged by said third line and adjustable to vary the path traveled by said element 60 when actuated by said third line.

10. In material-moving apparatus, the combination of a scraper element, an inhaul line and a back-haul line operatively connected with said element, a third, hauling, 65 line operatively connected with said element

and automatically shiftable from one end to the other of said elements to cause it to function alternately as an inhaul line and a back-haul line, for the purpose set forth, and a sheave engaged by said third line and adjustable to vary the path traveled by said element 70 when actuated by said third line.

11. In material-moving apparatus, the combination of a scraper element, an inhaul line and a back-haul line operatively connected with said element, a third line and a slideway along which said third line is movable along said element from one end to the other of the latter, for the purpose set forth, 75 and a sheave engaged by said third line and adjustable to vary the path traveled by said element when actuated by said third line.

12. In material-moving apparatus, the combination of a scraper element, an inhaul line and a back-haul line operatively connected with said element, a third line, and a slideway on said element along which said third line is movable along said element from one end to the other of the latter, for the purpose set forth, 80 and a sheave engaged by said third line and adjustable to vary the path traveled by said element when actuated by said third line.

13. In material-moving apparatus, the combination of a scraper element, an inhaul line and a back-haul line operatively connected with said element, a third line, and a laterally yieldable slideway adjacent said element and along which said third line is movable along said element from one end to 90 the other of the latter, for the purpose set forth, and a sheave engaged by said third line and adjustable to vary the path traveled by said element when actuated by said third line.

14. In material-moving apparatus, the combination of a scraper element, an inhaul line and a back-haul line operatively connected with said element, a third line, stops adjacent opposite ends of said element, and a 95 slideway along which said third line is movable into engagement alternately with said stops, for the purpose set forth, and a sheave engaged by said third line and adjustable to vary the path traveled by said element when actuated by said third line.

15. In material-moving apparatus, the combination of a scraper element, an inhaul line and a back-haul line operatively connected with said element, and a power-operated third, inhaul and back-haul, line operatively connected with said element and operative, independently of said first-named inhaul line, to move said element in paths at angles to the respective paths traveled by 100 said element when the latter is operated solely by said first-named inhaul and back-haul lines, respectively, and a sheave engaged by said third line and adjustable to vary the path traveled by said element when actuated by said third line.

16. In material-moving apparatus, the combination of a scraper element, an inhaul

line and a back-haul line operatively connected with said element, a third, power-operated, inhaul and back-haul line operatively connected with said element and operative independently of said first-named inhaul line, to move said element in paths at angles to the respective paths traveled by said element

when the latter is operated solely by said first-named inhaul and back-haul lines, respectively, and a sheave engaged by said third line and adjustable to vary the path traveled by said element when actuated by said third line. 10

HARRY A. ROE.
